BASE FOR TABLE LAMPS

Edwin I. Cole, Eagle, Wis., assignor to The Stiffel Company, Chicago, Ill., a corporation of Illinois

Filed Dec. 30, 1963, Ser. No. 77,955

Term of patent 7 years

(Cl. D48—20)

The figure is a perspective view of a base for table lamps showing my design.

The undisclosed side is the same in appearance as the side shown.

The dominant features of my design reside in the portions shown in full lines.

I claim:

The ornamental design for a base for table lamps, as shown and described.
